(57) **CLAIM**

The ornamental design for a shoe upper as shown and described.

DESCRIPTION

FIG. 1 is a front perspective view of a shoe upper in accordance with my new design;
FIG. 2 is a front view thereof;
FIG. 3 is a rear side view thereof;
FIG. 4 is a left side view thereof;
FIG. 5 is a right side view thereof;
FIG. 6 is a top view thereof; and,
FIG. 7 is a bottom view thereof.

The dash-dash broken lines shown in the drawings represent portions of the shoe upper as well as environmental structure of the shoe sole and form no part of the claimed design. The dot-dash broken lines define the bounds of the claimed design and form no part thereof.
